UNITED STATES PATENT OFFICE.

ROBERT P. GREENLEAF, OF CLEVELAND, OHIO, ASSIGNOR TO FRANK BILLINGS, OF CLEVELAND, OHIO.

LOADING MACHINE.

Application filed July 17, 1919. Serial No. 311,591.

To all whom it may concern:

Be it known that I, ROBERT P. GREENLEAF, a citizen of the United States, residing at Cleveland, in the county of Cuyahoga and State of Ohio, have invented a certain new and useful Improvement in Loading Machines, of which the following is a full, clear, and exact description.

This invention relates to a loading machine of the type having a shovel designed to be thrust forward to receive a load and to be swung upwardly and rearwardly over the machine to dump the material at the rear thereof.

The invention has for its principal object to provide a machine of this character which is extremely simple in construction, and durable, easy to construct and operate, and one wherein the working parts are not liable to be clogged by dirt or other materials being handled by the machine. Further the invention aims to provide in a machine of this type, a shovel elevating and swinging mechanism of a design and form such that the torque or turning moment exerted on the shovel is substantially proportional to the resistance to turning set up by the shovel, the effect being that during the early portion of the lifting movement of the loaded bucket, the turning moment exerted by the bucket shifting mechanism will be at a maximum, and will gradually decrease as the shovel is swung over the machine and as the leverage through which the loaded shovel acts is gradually reduced.

The invention may be briefly summarized as consisting in certain novel details of construction, and combinations and arrangements of parts which will be described in the specification and set forth in the appended claims.

In the accompanying sheets of drawings wherein I have shown one embodiment of the invention, Fig. 1 is a side view of the machine with the parts in the positions that they occupy at the beginning of the shovel filling or loading stroke; Fig. 2 is a top plan view of the same; Fig. 3 is a view similar to Fig. 1 on a reduced scale, showing the ram extended; Fig. 4 is a front view of the machine; Fig. 5 is a transverse sectional view substantially along the line 5—5 of Fig. 1; and Figs. 6 and 7 are side and plan views of a machine embodying a modification of my invention.

The machine includes a wheeled truck 10 on which are mounted the working parts of the machine, these being in the form of a superstructure which can be turned about a vertical axis, the truck being in this case 60 provided with arc-shaped tracks 11, and the superstructure with rollers 12 which engage the tracks and are guided thereon. The superstructure includes a forwardly and rearwardly moving part which carries the 65 shovel and serves to advance and retract the shovel during the filling and discharging operations. Various forms of movable shovel carriers may be employed and various means for actuating this part may be employed. The movable shovel carrier is hereinafter referred to as a "ram," the term "ram," however, should be understood to include any sort of forwardly and rearwardly movable support capable of performing the 70 75 functions above referred to.

The body of the superstructure is in this instance formed by a rather long horizontal cylinder 13 of a fluid pressure motor which is designed to reciprocate forwardly 80 and rearwardly a ram composed of a front member 14 connected to the plunger 15 of the motor and two side members 16 which extend rearwardly alongside the cylinder 13, this ram being therefore substantially U-shaped. The side members 16 of the ram are each formed in this case of angles and plates, including three angles 16^a, 16^b and 16^c with inwardly turned flanges, and connected together by one or more plates 16^d.

This ram and the parts carried by it are supported and guided for forward and rearward reciprocating movement by rollers and tracks, including two track bars 17, secured to opposite sides of the cylinder 13, these 90 track bars being engaged by upper and lower rollers 18 carried by the rear end of the ram and engaging the upper and lower faces of the bars, and the ram is further supported by forwardly disposed rollers 19 100 which are supported at the lower front portion of the cylinder 13, and are engaged by the flanges of the lower angles 16^c of the ram.

The ram is adapted to reciprocate, that is 105 to say, to move forwardly and rearwardly a material conveying or loading element consisting of a shovel 20, which as here shown, is substantially triangular in shape, having an open front and a bottom plate, the front 110

edge of which may be provided with teeth, and constitutes the digging or scooping part. This shovel is supported from the ram by swinging arms 21 which are connected to 5 opposite sides of the shovel and which during the filling stroke, or at least the early part of the filling stroke, extend downwardly and forwardly, and at such time they rest upon bumpers or stops 22 which are 10 carried by brackets 23 secured to the front side portions of the ram, which brackets may be adjusted to vary the inclination of the arms while they are resting on the bumpers.

15 It will be observed that the shovel supporting and actuating arms 21 have extensions 21^a which in this instance are at substantially right angles to the arms, so that each arm with its extension constitutes in 20 effect a bell-crank. These arms 21 at their upper or inner ends 25, or at the junction of the arms and the extensions 21^a thereof, are pivotally mounted on pins or studs carried by a carriage or trolley 26, having 25 rollers 27, designed to travel back and forth in guideways 28 in the side members of the ram. The carriage or trolley 26 is composed of side members connected together at the front by a cross-head 29, which is attached 30 to the plunger 30 of a fluid pressure reciprocating motor 31 which is carried by the ram, and is in this case above the cylinder 13 of the lower motor which actuates the ram.

35 It will be seen from the description so far given, that when the lower motor is operated, the ram and all parts carried by it, including the shovel, shovel supporting arms, carriage or trolley 26, and upper motor 31, are moved forwardly or rearwardly. It will be seen also that when the upper motor 31 is operated, the carriage or trolley, the shovel and the shovel supporting arms are moved forwardly or rearwardly, or are 40 given a movement of translation relative to the ram.

During this movement of translation of the shovel and shovel supporting arms it is desirable that the arms and shovel be 45 given a turning or rotary movement so that the shovel will be swung over the machine to dumping position, and back to digging position. It is in the mechanism for imparting this turning movement, preferably simultaneously with the movement of translation, that the present invention resides particularly.

In a patent granted to Frank Billings and myself on the 26th day of November, 1918, 50 No. 1,286,168, for a loading machine, which in some respects is similar to that constituting the subject matter of this invention, the turning movement is imparted to the shovel arms during the movement of translation 55 thereof by means of gear segments which

engage and roll over racks carried by the ram.

In accordance with the present invention, turning devices are provided between the ram and the arms, the turning means differing from that in the Billings and Greenleaf patent in the respect, broadly stated, that the turning device or means carried by either the arm or ram cooperate with a given or certain point of the other part. 70 75

In the construction shown in Figs. 1 to 5, turning devices in the form of links 32 pivoted to the side portions of the ram at 33 impart the turning movement to the shovel and arms, and in this instance these links 80 co-operate with given or certain points of the arms,—in this instance the free ends of the arm extensions 21^a to which the links are pivotally connected.

When the carriage is retracted, the tendency of these links is to resist the backward movement of the carriage, shovel and shovel supporting arms, and as the carriage is pulled back by the motor 31, these links exert a turning effort on the shovel supporting arms, the torque depending, of course, upon the effective leverage afforded by the arm extensions 21^a. This leverage is greatest while the shovel is traveling from its lowermost position upwardly to a position 85 in front of the machine or in line with the ram, and is at a maximum when the arm extensions 21^a are at right angles to the links 32, and is gradually reduced as the arm extensions 21^a and links 32 approach parallelism. 90 In other words, the turning effort or torque exerted on the shovel supporting arms is greatest when the resistance to turning is at a maximum, due to the fact that the load of the shovel is acting through the maximum leverage. 95 As the shovel is swung over the machine the leverage of the load is gradually reduced until the shovel supporting arms are vertical, but this condition is accompanied by a gradual reduction 100 in the turning effort or torque exerted by the links 32, the two increasing and decreasing substantially proportionately as is desired to obtain a smoothly working and powerful machine. 105

In operation the shovel is swung downwardly in front of the machine, and is given a forward filling stroke by the actuation of the motor which shifts the ram, or by the 110 conjoint actuation of the ram operating and carriage operating motors, the motors being operable either successively or simultaneously. When the shovel is filled, and is either in its lowermost position or partly elevated, the ram will be retracted and during the retraction, or after the retraction, the shovel will be swung upwardly and rearwardly over the machine so as to dump the 115 contents thereof into a suitable receiving receptacle such as a mine car, this being done 120 125 130

by the retraction of the carriage 36 through the upper motor 31, and by the reaction of the links 32. After the shovel has been dumped it is swung downwardly and forwardly to digging position by moving the carriage forwardly to its foremost position in the guide slots or guide-ways of the ram, whereupon the operation may be repeated.

In addition to the fact that the particular shovel actuating mechanism here shown and described exerts a torque which is substantially proportional to the resistance to turning and lifting, the construction embodies the features of great simplicity, durability, and ease and low cost of construction. Furthermore, the parts are not liable to be deranged or clogged by dirt or other foreign matter.

In the modification shown in Figs. 6 and 7, substantially the same results are obtained with a somewhat different construction. Instead of the links, I provide channel-shaped guides 34 which are engaged by rollers 35 at the free ends of the arm extensions 21^a. These guides which may be in the form of castings, are secured to the ram by brackets 36. The grooves or channels of the guides extend diagonally upward from a point below the guide-ways 28 of the ram along which the carriage or trolley moves to a point above the same, and in this instance the guides 34 provide curved paths for the rollers at the free ends of the arm extensions 21^a. These curved paths may be arcs of circles similar to the curved paths or arcs through which the axes of connection between the links 32 and arm extensions 21^a travel in the construction first described, although I do not regard it as essential that curved paths be provided or that these paths be in the form of arcs of circles if curved.

The construction may be otherwise modified, for the frame and the reciprocating parts, such as the ram or carriage need not be constructed as here shown, and while I have here illustrated fluid pressure reciprocating motors which are preferably operated by air, other types of motors may be utilized, such as rotary motors which can be operated by other sources of power than air, such as electricity. I therefore aim in my claims to cover all modifications which do not involve a departure from the spirit and scope of my invention in its broadest aspects.

Having described my invention, I claim:

1. In a loading machine, a frame, a ram movable forwardly and rearwardly with respect to the frame, a shovel adapted to be swung from in front of the machine upwardly and rearwardly to dump material at the rear thereof, an arm connecting the shovel to the ram and mounted on the latter for rotary movement and for forward and rearward movement relative thereto, the arm

and ram having means comprising a rigid element connected to one part and engaging the other part at a certain or given point for imparting a rotary movement to the arm in one direction when it is moved forwardly with respect to the ram and a rotary movement in the reverse direction when it is moved rearwardly with respect to the ram. 70

2. In a loading machine, a frame, a ram movable forwardly and rearwardly with respect to the frame, a shovel adapted to be filled with material at the front of the machine and to be swung upwardly and rearwardly over the machine and back again to digging position, a member movable forwardly and rearwardly of the ram, an arm connected with the shovel and pivotally connected to said member, the arm and ram having means comprising a rigid element connected to one part and engaging the other part at a certain or given point for imparting a rotary movement to the arm in one direction when it is moved forwardly with respect to the ram and a rotary movement in the reverse direction when it is moved rearwardly with respect to the ram. 80

3. In a loading machine, a frame, a ram movable forwardly and rearwardly with respect to the frame, a shovel adapted to be filled with material at the front of the machine and to be swung upwardly and rearwardly over the machine and back again to digging position, a member movable forwardly and rearwardly of the ram, an arm connected with the shovel and pivotally connected to said member, said arm and ram having means for imparting a turning movement to the arm when said member is moved forwardly or rearwardly relative to the ram, said means including a device carried by one part and co-operating with a given or certain point of the other part, said arm comprising a main portion extending from the shovel to said member, and an extension projecting beyond the pivotal connection with said member and constituting a part of the turning means. 90

4. In a loading machine, a frame, a ram movable forwardly and rearwardly with respect to the frame, a shovel adapted to be filled with material at the front of the machine and to be swung over the machine to dump the material at the rear thereof, an arm connecting the shovel to the ram and adapted to be turned and to be given a forward and rearward movement of translation relative to the ram, and means on the ram and co-operating with a given or certain point of the arm to impart a turning movement to the arm during its movement of translation. 100

5. In a loading machine, a frame, a ram movable forwardly and rearwardly with respect to the frame, a shovel adapted to be filled with material at the front of the ma- 110 120 125 130

chine and to be swung over the machine to dump the material at the rear thereof, an arm connecting the shovel to the ram and adapted to be turned and to be given a forward and rearward movement of translation relative to the ram, and means on the ram and co-operating with a given or certain point of the arm to impart a turning movement to the arm during its movement of translation, said arm having an extension with which said means co-operates.

6. In a loading machine, a frame, a ram movable forwardly and rearwardly with respect to the frame, a shovel adapted to be filled with material at the front of the machine and to be swung over the machine to dump the material at the rear thereof, an arm connecting the shovel to the ram and adapted to be turned and to be given a forward and rearward movement of translation relative to the ram, and means on the ram and co-operating with a given or certain point of the arm to impart a turning movement to the arm during its movement of translation, said arm being in the form of a bell-crank and having one arm extending to the shovel, and another arm with which said means co-operates.

7. In a loading machine, a frame, a shovel adapted to receive a load at the front of the machine and to be swung over the machine to dump the material at the rear thereof, a ram movable forwardly and rearwardly of the frame, a member movable forwardly and rearwardly with respect to the ram, an arm connecting the shovel to said member, and an arm connected to the ram and co-operating with said first-named arm to tilt the latter and the shovel.

8. In a loading machine, a frame, a shovel adapted to receive a load at the front of the machine and to be swung over the machine to dump the material at the rear thereof, a member movable forwardly and rearwardly to carry the shovel forwardly and rearwardly, a shovel supporting and actuating arm connected to the shovel, means for moving said shovel and arm forwardly and rearwardly with respect to said member, and means for causing a tilting or turning movement to be imparted to the shovel and arm during the movement relative to the said member, comprising an arm connected to said member and co-operating with said

first-named arm so as to exert a torque or turning effort on said first-named arm.

9. In a loading machine, a frame, a shovel adapted to receive a load at the front of the machine and to be swung over the machine to dump the material at the rear thereof, a ram movable forwardly and rearwardly of the frame and supporting the shovel, a shovel supporting and actuating arm, means for giving said arm and shovel a movement of translation relative to the ram, and a link connecting said arm to the ram and exerting a turning effort on the former during said movement of translation.

10. In a loading machine, a frame, a shovel adapted to receive a load at the front of the machine and to be swung over the machine to dump the material at the rear thereof, a ram movable forwardly and rearwardly of the frame, a member movable forwardly and rearwardly of the ram, an arm connecting the shovel to said member, and a second arm pivotally connecting said first-named arm to the ram and serving to exert a turning effort on said first-named arm when the latter and the shovel are given a movement of translation relative to the ram.

11. In a loading machine, a frame, a shovel adapted to receive a load at the front of the machine and to be swung over the machine to dump the material at the rear thereof, a ram movable forwardly and rearwardly, a carriage movable forwardly and rearwardly of the ram, an arm connecting the shovel to the carriage and having an extension, and a link connecting said extension to the ram.

12. In a loading machine, a frame, a shovel adapted to receive a load at the front of the machine and to be swung over the machine to dump the material at the rear thereof, a ram movable forwardly and rearwardly of the frame, a trolley movable forwardly and rearwardly of the ram, a bell-crank pivoted to said trolley and having one part connected to the shovel, and a link connecting the other part of said bell-crank to the ram whereby when the trolley is given a movement of translation relative to the ram a turning effort is exerted on the bell-crank and shovel.

In testimony whereof I hereunto affix my signature.

ROBERT P. GREENLEAF.
